ROTATABLE SIGN OR SIMILAR ARTICLE

Clark L. Lofgren, Golden Valley, Minn., assignor to The Cornelius Company, Anoka, Minn., a corporation of Minnesota

Filed Dec. 3, 1968, Ser. No. 14,754

Term of patent 14 years

Int. Cl. D20—02

U.S. Cl. D96—12

FIG. 1 is a side elevational view of a rotatable sign or similar article showing my new design, the opposite side being a mirror image of the side shown.

FIG. 2 is a rear elevational view thereof.

FIG. 3 is a front perspective view thereof.

I claim:

The ornamental design for a rotatable sign or similar article, substantially as shown and described.
